UNITED STATES PATENT OFFICE.

CARL WILHELM MODEL, OF STUTTGART, GERMANY.

MACHINE FOR POLISHING KNIVES.

SPECIFICATION forming part of Letters Patent No. 628,016, dated July 4, 1899.

Application filed March 14, 1898. Serial No. 673,823. (No model.)

To all whom it may concern:

Be it known that I, CARL WILHELM MODEL, a citizen of the Kingdom of Würtemberg, residing at Feuerbach-Stuttgart, Germany, have 5 invented a new and useful Improvement in Knife-Polishing Machines, of which the following is a specification.

This invention relates to means for polishing knives; and its object is to provide a machine which will be particularly useful for manipulation by hand and in which the introduction of the knife-blade will not interfere with the driving mechanism. Its object is, moreover, to provide a suitable guide for 15 maintaining knives of different thicknesses in proper position with relation to the polishing or abrading machine and also to provide an effectual means for mounting the polishing or cleaning wheels on their shafts.

With these objects in view my invention consists in the means, features, and combination of parts hereinafter described, and more particularly pointed out in the claims.

In the following detailed description of the 25 manner in which I carry my invention into effect reference is made to the accompanying drawings, in which—

Figure 1 represents a side elevation of a knife-polishing machine embodying my invention; Fig. 2, a plan view thereof, and Fig. 3 a diametrical section of one of the polishing or abrading disks.

By referring to the drawings it will be noticed that the machine embodying my invention comprises two polishing rollers or disks A A', which are fixed or keyed on the parallel horizontal shafts B B', the said shafts being journaled in the frame G of the machine at such a distance from each other that the 35 two disks A A' will touch, or nearly touch. The point of contact is the place where the knife-blades to be cleaned and polished are inserted. The shafts B B' are provided at a point outside of the supporting-frame G with the cog-wheels c c', respectively. The cog-wheels c c' mesh with similar cog-wheels C C', journaled in the frame G below the cog-wheels c c'. The cog-wheels C C', and therefore their companion cogs c c', are rotated 45 from a horizontal shaft F, driven by any suitable power by means such, for example, as the crank f, through the medium of the bevel-

eled cogs D D', fixed on the shaft F, and the corresponding beveled cogs d d', meshing with the former and fixed to the shaft of the 55 cog-wheels C C'. By this means it will be noted that I am enabled to drop the main shaft F considerably below the point at which the knife-blade is introduced into the bite of the polishing-disks A A'. I am thus enabled 60 to arrange the actuating parts of the knife-polisher in such a way that the knife-blade when inserted into the machine and protruding beyond the polishing-disks will in no way interfere with said actuating means. At the 65 same time this construction enables me to bring the said actuating or driving means closely up to the main frame G and the polishing-disks. It is obvious that this results in a much more compact structure, whereby 70 the same takes up less space and may be made stronger with a less amount of material than the polishing-machines hitherto known.

Another feature of my invention consists in the manner of mounting the polishing-disks 75 on their shafts. This is best disclosed in Fig. 3, from which it will be noted that a polishing-disk under my invention consists of an iron core or pulley a, which pulley is fixed to the shaft B or B' in any suitable way. On 80 the periphery of the core or pulley A is seated a ring or annulus r, of ebonite or hard rubber, the latter being in turn encircled by a ring or annulus o, of soft rubber, preferably made of considerable thickness. On the latter soft-rubber ring o finally is mounted the outer ring or coating, consisting of any suitable material for polishing and cleaning or abrading, such as leather or felt. The hard-rubber or ebonite ring r is fixed upon the iron 85 core or pulley A in any suitable way—such, for example, as by dovetailed joints, slots and tenons, or the like. The soft-rubber ring is mounted on the ebonite or hard-rubber ring without any further provision, being held firmly thereon by means of its elasticity and friction, as will be understood. The polishing-disk A is fixed with respect to the frame G, while the other disk A' may be 90 yieldingly journaled in said frame G, as shown. The means for accomplishing this are briefly as follows: The shaft B' of the said disk A' is journaled in a horizontal yoke or strap H, embracing the frame G, as shown 95

best in Fig. 2, a horizontal slot being provided in said frame G, which will permit of the horizontal movement of the journal portion of the strap or yoke in the said frame. The 5 yoke H, and with it the disk A', are yieldingly pressed toward the disk A by means of a spiral spring i', which bears against said yoke at one end and encircles a stem i, secured to and extending from the frame G. The other 10 end of the spring i' bears against a nut h', engaging the outer threaded portion of the stem i. By adjusting the nut h' on the threaded stem i the tension of the spring i', and hence the yielding pressure of the disk 15 A' against the disk A, may be increased or diminished.

A further feature of my invention consists 20 in the adjustable guides for the knife-blade to be polished. These consist of a shelf M, arranged, preferably, adjustably on the frame G at a point opposite to or somewhat below the point of contact of the disks A A'. This shelf M may be rendered vertically adjustable by means of a slot and set-screw m, as 25 shown. Upon the shelf M are mounted the two guards M' M', consisting of the upwardly-extending wings m², which, as shown, are upwardly flaring and form the guiding groove or slot, into which the protruding portion of 30 the knife-blade passes as it is introduced between the polishing-disks and the lower horizontal wings m³, which rest upon the shelf M. Each guard M' is made horizontally adjustable by any suitable means, such as the 35 set-screw-and-slot connection shown in the drawings. By this means the knife-guide is rendered adjustable, so as to be adapted to receive knife-blades of different thicknesses.

In operation the knife is inserted between 40 the two abrading or rubber disks A A', and its protruding end is inserted into the guard M' with the one hand, preferably the left hand. The crank F is then turned and its movement through the gearings D D' d d' C C' 45 c c' is imparted to the shafts D D' and the disks A A', and the knife, being drawn back and forth in the bite of the abrading-disks, is polished. If the pressure of the abrading-

disks is too great or too small, it is readily adjusted by manipulating the nut h'. By shifting the shelf M vertically and the guards M' M' 50 horizontally with respect to each other the machine may readily be adjusted to suit knife-blades of different thicknesses and widths. The knife-guard at the same time provides 55 an effectual means for preventing the knife-blade from injuring or being injured by the abrading or polishing roller, while at the same time all contact with the driving portions of the mechanism is obviated by the arrangement forming part of my invention, whereby I am enabled to drop the main shaft F.

What I claim, and desire to secure by Letters Patent, is—

1. In a machine for polishing knives, a pair 65 of polishing rollers or disks each provided with an operating-gear on its shaft, intermeshing gears arranged below the shafts of said rollers or disks, with their axes parallel to said shafts, and a main driving-shaft arranged at right angles to and intersecting the axes of the lowermost gears, and engaging therewith, substantially as shown and described.

2. A disk for polishing, and a similar machine consisting of a central core, a ring or annulus of hard rubber surrounding the same and fixed thereon, a second ring or annulus of soft rubber mounted on the latter and maintained thereon of its own elasticity and 80 friction and an outer covering or rim of polishing material, substantially as set forth.

3. In a polishing-machine the combination with a pair of polishing-disks of a vertically-adjustable shelf arranged near the point of 85 contact of the said disks, and a pair of horizontally-adjustable guards mounted on said shelf and forming a guide for the knife to be polished.

In testimony whereof I affix my signature 90 in presence of two witnesses.

CARL WILHELM MODEL.
